UNITED STATES PATENT OFFICE.

GIANNI BETTINI, OF NEW YORK, N. Y.

PORTABLE SPARKING LIGHTER.

Application filed May 29, 1926. Serial No. 112,482.

This invention relates to portable lighters, and with respect to its more specific features to lighters employing a sparking member and which are adapted conveniently to be carried 5 in the pocket or in a small case.

One of the objects of the invention is the provision of a lighter of the character referred to which shall be especially practical and convenient in use.

10 Another object of the invention is the provision of a lighter of the character referred to, the operation of which is very simple and in which the element of skill of the operator is quite eliminated, and which avoids incommoding the operator, whether by soiling 15 the fingers, the production of blisters or callouses, the injury to gloves, and the like; many of which objections pertain to some portable lighters.

20 The device is especially convenient and suitable for use by either sex, and eliminates many of the objections pertaining to such devices when used by the fair sex.

Another object of the invention is the provision of a portable lighter of the character referred to, the sparking action of which may be certainly effected merely by a setting of the operating parts in a certain relative position, the setting requiring no skill or 25 particular ability on the part of the operator, the whole action being readily accomplished by one hand.

30 Another object of the invention is the provision of a portable lighter of the character described in which the sparking member may be renewed by simple manipulation and without dismantling the device.

35 The invention accordingly comprises the features of construction, combinations of elements, and arrangement of parts, which will be exemplified in the construction herein-after set forth and the scope or the application of which will be indicated in the claims.

40 For a fuller understanding of the nature and objects of the invention reference should be had to the following detailed description taken in connection with the accompanying drawing in which

45 Fig. 1 is a perspective view of one embodiment of the invention, parts being broken away to more clearly show details of construction.

Fig. 2 is a plan view of Fig. 1, on a smaller scale, and with the operating lever in a different position. 55

Fig. 3 is a view looking at the top of Fig. 2 and partly in section, and with some of the parts removed to more clearly disclose details.

Fig. 4 illustrates a portion of the device 60 in vertical, longitudinal section, on line 4—4.

Fig. 5 is a plan view showing a modified form of wick cover and its actuating device.

Fig. 6 is a vertical section of Fig. 5, on line 6—6. 65

Fig. 7 is a diagrammatic view, in elevation, of a further modification.

Referring now more specifically to the drawing, and particularly to the form illustrated in Figs. 1 to 4, the frame and metal fuel reservoir is indicated by the numeral 1, having a filling opening at the top, closed by a pivoted lid 2. Opening into the end wall of the reservoir is a tube 3, which may be closed by a cap or strap 4, the tube 3 being closed at its inner end and adapted to serve as a receptacle, partitioned from the fuel, as, for instance, a receptacle for a lip stick. On the side wall of the reservoir is a large glass mirror 5. 70

A wick leads from the kerosene, or other liquid fuel, in the reservoir through the top 6. Adjacent the top, or lighting end, of the wick is the sparking member 7 and the abrader member 8, the wick being in the path of sparks coming from the sparking member. The sparking member may be made of a pyrophoric alloy, as, for instance, an alloy containing cerium and iron. The abrader member may be of steel. 80

For pressing the abrader and sparking members into contact with each other, the spring 9 is employed. In the embodiment illustrated the spring is of bow shape, one end pressing against the rear of the sparking member 7, and the other end having an eye engaging a pin 10 at the end of an adjusting screw 11 working in a stationary lug 12 upstanding from top 6. Partially surrounding and guiding the member 7 is a short 85 channel member or guide 13, slotted at its bottom, as at 14, for passage of the end of spring 9. In the upper end of the lighter is the recess 15, into which spring 9 may ex- 100

tend and by the wall of which this spring is restrained from lateral movement, and kept apart from the fuel in the reservoir. By inserting a tool, as the end of a small screw driver into a recess 15, the end of spring 9 may readily be withdrawn from the guide 13, so as to permit discharge of one sparking member 7 and replacement by another, without dismantling the device.

10 In the present embodiment the relative movement between the abrader 8 and the sparker 7 to produce sparking is effected by a spring 16. Although either of these members may be the part moved to effect such 15 result, and though these members may be of different shape from that illustrated, in the present embodiment the abrader member 8 is the member directly moved by the spring and is a wheel or of disc shape and has teeth 20 on its periphery whereby it is adapted more effectively to abrade the member 7. For connecting the spring 16 to the abrader member 8, the latter is affixed to a shaft 17, rotatably mounted in the lighter. Extending 25 from the top 6 is a tubular bearing member 18, the shaft 17 being supported in a stationary block 19, carried in the tubular member 18. At its upper end the shaft extends through and bears in a plate 20 which 30 is spaced above and fixed to the top 6, as will appear more particularly hereinafter. In the embodiment illustrated in Figs. 1 to 4, the spring 16 is of helical form and has one end fixed to the stationary block 19, 35 the other end being fixed to shaft 17, which latter extends through the spring.

Affixed to the upper end of shaft 17 is a 40 manually operable lever, the handle arm 21 of which is relatively long, the lever also having a relatively short nose 22, which depends toward top 6 and is adapted to actuate a wick-cover. In Fig. 2 the handle arm 21 lies close to the side wall of the reservoir 1, and at its end 23, this arm projects from 45 the adjacent lighter part so as readily to permit it to be manipulated by the finger of the hand of the user. Also in the position illustrated in Fig. 2, the adjacent part of the lighter provides a stop to arrest movement of the arm 21. As shown, the lug 12 50 serves the purpose of the stop referred to.

In the embodiment shown in Figs. 1 to 4, a vapor chamber is provided adjacent the wick 23. Depending from the bearing plate 55 is the flange 24, which in conjunction with the bearing plate and the adjacent portion of the top 6 provides the vapor chamber. Lateral projection of flange 24 provides the guide 13 hereinbefore mentioned. The lighting end of wick 23 emerges into the vapor chamber, and vapor and oil tend to accumulate in this chamber, so that when sparking occurs, this vapor and oil becomes ignited and assist in igniting the wick. The wick 60 may be any substance capable of being ig-

nited by the sparks. In the present embodiment it is of cotton providing fine threads, or tinder, at the end to be lighted.

Immediately above the wick the vapor chamber has an opening adapted to be opened 70 and closed by the wick cover 25. This cover is pivoted at 26 to the top 6 for horizontal movement and has an arm 27 the end of which, in the embodiment now referred to, is adapted to move into and out of the 75 path of the nose 22 of the manually operable lever. Carried by the wick cover arm are two flat surfaces 28 and 29 adapted to co-operate with the plate spring 30, which latter thereby yieldingly holds the wick cover 80 in either open or closed position relative to the opening in the vapor chamber. When the cover closes said opening the flame of the wick is snuffed out. When the cover is open, the flame is conveniently accessible.

When the lighter is in the pocket or bag, the parts are generally in the relation shown in Fig. 2. Upon removal from the pocket the lever arm 21 may readily be rotated by a finger of the hand in the direction of the arrow Fig. 2. This action will result in altering the tension of the spring 16 so as to impart thereto tension as required to effect relative movement between the abrader and the sparking member, and upon release of the lever, the spring 16 will cause the abrader member quickly to rotate in the opposite direction relative to the sparking member 7, and the resultant friction and abrasion will result in production of a shower of sparks which will be directed toward and light the wick. During the movement of the lever in the direction of the arrow, the wick cover 25 will be moved from the opening in the vaporizer chamber, so that the wick will 95 be exposed to the air preliminary to the sparking. The initial opening movement of the wick cover is effected by the nose 22 of the manually operative lever. Toward the end of the opening movement of the wick 100 cover, the spring 30 will cooperate with the flat face 29, to complete its movement and to hold it in open position and to hold the arm 27 out of the path of the nose 22. The 105 return or retractive movement of the manually operable lever is also quickly effected by the spring 16, being arrested by the handle 21 coming into contact with the stop before mentioned, and when so arrested the lever is in initial position ready for a succeeding operation. But it will be noted that the wick cover is held open by the spring 30, until purposely closed by the hand.

Hence repeated operations of the lever 21 110 may be made while the cover is open. Also it will be noted that when the lever is in retracted position, the cover may be closed independently of any movement of the lever. By pressing the spring 9 out of the guide 13 by a suitable tool, the sparking 115 120 125 130

member 7 may be shaken out of the guide and replaced by another. For best efficiency a portion of the vapor chamber should be in the path of the sparks between the sparking member and the wick, and in this embodiment this object is secured by having the abrader member 8 and the end of the wick wholly enclosed in the vapor chamber, as illustrated. By this construction the abrader member is inaccessible for operation except through the lever.

Instead of a horizontally movable wick cover, a vertically movable one may be used as illustrated in Figs. 5 and 6, in which the wick cover is a thimble-like member 31, pivoted on an upstanding bearing 32, for vertical movement and having an arm 33 in the path of the nose 22. The thimble 31 enters the opening in the vapor chamber, and may have a lateral flange 34 to completely close said opening. Also it is to be observed that the invention viewed in certain aspects, contemplates that the vapor chamber may be omitted.

In the modification illustrated diagrammatically in Fig. 7, the abrader member is indicated at 35, rotatively mounted on a standard 36 and having a manually operable lever 37 fixed to the shaft of the abrader and to which one end of a lever actuating spring 38 is connected, the other end of the spring being fixed to a pin 39 on the fuel reservoir 1. The sparking member appears at 40, being held in a tube 41, the spring 42 and screw 43 serving to effect contact between the abrader and sparkler. The wick is indicated at 44, and may have a removable cover, not shown. On pressing the lever 37 to the left (Fig. 7) the spring 38 will be tensioned so that, on release of the lever, it will rotate the abrader 35, and cause sparking and ignition of the wick.

Thus by the above described construction are accomplished, among others, the objects hereinbefore referred to.

Since certain changes may be made in the above article and different embodiments of the invention could be made without departing from the scope thereof, it is intended that all matter contained in the above description or shown in the accompanying drawing shall be interpreted as illustrative and not in a limiting sense.

Having described my invention, what I claim as new and desire to secure by Letters Patent, is:—

1. A portable lighter including, in combination, a sparking member, an abrader adapted to contact therewith, a spring operatively connected to cause relative abrading movement between said parts to produce sparking, a wick cover, means including a manually operable lever fixed to said abrader and operatively connected to im- part to said spring the tension required to

effect said relative movement and to impart opening movement to said cover preliminary to said sparking, and means mounting said cover for movement from open to closed position while said lever is in spring re- 70 tracted position.

2. A portable lighter including, in combination, a sparking member, an abrader adapted to contact therewith, a spring operatively connected to cause relative abrading 75 movement between said parts to produce sparking, a wick cover, and a manually operable lever operatively connected to impart to said spring the tension required to effect said relative movement and to impart open- 20 ing movement to said cover preliminary to said sparking, said operative connections including an arm carried by said cover adapted to be moved by said lever to impart said opening movement, and a spring adapted 25 to coact to move said arm out of opera- 85 tive relation to said lever at the end of said opening movement.

3. A portable lighter including, in combination, a sparking member, an abrader 90 adapted to contact therewith, a spring operatively connected to cause relative abrading movement between said parts to produce sparking, a rotatable shaft to which one end of said spring is connected, said abrader being a wheel affixed to said shaft, a manually operable lever affixed to said shaft, and a pivoted wick cover having an arm, said lever having a nose movable in a path intersecting that of said arm. 100

4. A portable lighter including, in combination, a sparking member, an abrader adapted to contact therewith, a spring operatively connected to cause relative abrading movement between said parts to produce 105 sparking, a rotatable shaft to which one end of said spring is connected, said abrader being a wheel affixed to said shaft, a manually operable lever affixed to said shaft, a pivoted wick cover having an arm, said lever having a nose movable in a path intersecting that of said arm, a wick, and a chamber enclosing said wheel and the lighting end of said wick, having an opening adapted to be closed by said cover. 110

5. In a portable lighter, in combination, a manually operable lever, a shaft affixed to said lever to be rotated by rotation of the latter, a shaft rotating helical spring connected to said shaft and to a relatively stationary part of the lighter, a sparking member, an abrader member, one of said members being rotative with said shaft, a wick, a pivotally mounted cover for the top of said wick, and a cover actuating arm in the path of movement of said lever. 115

6. In a portable lighter, in combination, a manually operable lever, a shaft affixed to said lever to be rotated by rotation of the latter, a shaft rotating helical spring con- 120

nected to said shaft and to a relatively stationary part of the lighter, a sparking member, an abrader member, one of said members being rotative with said shaft, a wick, 5 and a vapor chamber in which the top of said wick lies having a removable cover above said wick.

7. In a portable lighter, in combination, a manually operable lever, a shaft affixed to 10 said lever to be rotated by rotation of the latter, a shaft rotating helical spring connected to said shaft and to a relatively stationary part of the lighter, a sparking member, an abrader member, one of said members being rotative with said shaft, a wick, 15 a vapor chamber in which the top of said wick lies having a removable cover above said wick, and operative connections whereby movement of said lever in one direction 20 of rotation removes said cover.

8. A portable lighter including, in combination, a sparking member, an abrader adapted to contact therewith, a spring operatively connected to cause relative 25 abrading movement between said abrader and member to produce sparking, a manually operable lever operable in one direction to impart to said spring the tension required to effect said relative movement and retract- 30 ed in the opposite direction by said spring, a wick cover movable to open and closed positions, and means whereby movement of said lever to tension said spring is adapted to cause opening movement of said cover.

35 9. A portable lighter including, in combination, a sparking member, an abrader adapted to contact therewith, a spring operatively connected to cause relative abrading movement between said abrader and member 40 to produce sparking, a manually operable lever operable in one direction to impart to said spring the tension required to effect said relative movement and retracted in the opposite direction by said spring, a wick 45 cover movable to open and closed positions, and means whereby movement of said lever to tension said spring is adapted to cause opening movement of said cover, said cover mounted for closing movement, independ- 50 ently of said lever, between successive spring-retracted sparking movements between said abrader and sparking member.

55 10. A portable lighter including, in combination, a sparking member, an abrader adapted to contact therewith, a spring operatively connected to cause relative abrading movement between said abrader and member to produce sparking, a manually operable lever operable in one direction to impart to 60 said spring the tension required to effect said relative movement, and retracted in the op-

posite direction by said spring, a wick cover movable to open and closed positions, and means whereby movement of said lever to tension said spring is adapted to cause opening movement of said cover, said cover being movable to open and closed positions independently of said lever when the latter is in spring retracted position.

65 11. A portable lighter including, in combination, a sparking member, an abrader adapted to contact therewith, a spring operatively connected to cause relative abrading movement between said abrader and member to produce sparking, a manually operable 70 lever operable in one direction to impart to said spring the tension required to effect said relative movement, and retracted in the opposite direction by said spring, a wick cover movable to open and closed positions, 75 a fuel reservoir on the outside of which said sparking member, abrader, lever and cover are mounted closely adjacent each other, said lever including a protruding, finger-manipulative lever-arm portion, freely accessible 80 laterally of the lighter, the lever arm being movable laterally into and out of contact with the lighter.

85 12. A portable lighter including, in combination, a sparking member, an abrader adapted to contact therewith, a spring operatively connected to cause relative abrading movement between said abrader and member to produce sparking, a manually operable 90 lever operable in one direction to impart to said spring the tension required to effect said relative movement and retracted in the opposite direction by said spring, a wick cover movable to open and closed positions, 95 and means mounting said lever for repeated spring-tensioning and retractive movements while said cover is open.

100 13. A portable lighter including, in combination, a sparking member, an abrader adapted to contact therewith, a spring operatively connected to cause relative abrading movement between said abrader and member to produce sparking, a manually operable lever operable in one direction to impart to 105 said spring the tension required to effect said relative movement and retracted in the opposite direction by said spring, a wick cover movable to open and closed positions, and means whereby movement of said lever to tension said spring is adapted to cause 110 opening movement of said cover, said lever adapted for repeated spring-tensioning and retractive movements while said cover is open.

115 In testimony whereof I affix my signature.

GIANNI BETTINI.
